UNITED STATES PATENT OFFICE.

JOHN BOOTH, OF BELLVILLE, TEXAS.

WELL-STRAINER.

SPECIFICATION forming part of Letters Patent No. 604,651, dated May 24, 1898.

Application filed September 22, 1897. Serial No. 652,642. (No model.)

To all whom it may concern:

Be it known that I, JOHN BOOTH, a citizen of the United States, residing at Bellville, in the county of Austin and State of Texas, have 5 invented certain new and useful Improvements in Well-Strainers; and I do hereby declare the following to be a full, clear, and exact description of the invention, such as will enable others skilled in the art to which it 10 appertains to make and use the same.

My invention relates to improvements in well-strainers, and has for its object to provide a well-strainer of such a construction that by simply varying its size it may be adapted 15 for use in large or small wells and by varying its shape it may be used in wells of any desired shape, and that without modifying the essential features of the strainer.

My invention will be clearly understood 20 by reference to the accompanying drawings, wherein the same parts are indicated by the same letters in the corresponding views.

Figure 1 represents a side elevation of a portion of a section of well-strainer constructed 25 according to my invention in a hexagonal form, and Fig. 2 represents an end elevation of the same. Fig. 3 represents a view similar to Fig. 2, showing another form of strainer. Fig. 4 represents a view similar to Figs. 2 and 30 3, illustrating still another form of strainer; and Fig. 5 represents a side elevation of the cylindrical form of strainer shown in Fig. 4.

In Figs. 1 and 2, A represents a strainer of a hexagonal form, composed of rectangular 35 side pieces A', beveled at their side edges and fitted together, as at a', and held together by any suitable means. Each of these side pieces A' is provided with a plurality of larger, preferably circular, openings A⁰, which extend about half-way therethrough from the outer side and connect with smaller, preferably circular, openings a⁰, which extend to the inner side of the side piece A'. Within the bottom or inner end of the larger opening A⁰ and over the inner end of the smaller opening a⁰ is fitted and secured a piece of wire-gauze a², and over the outer end of the larger opening A⁰ is also fitted another piece of wire-gauze a³, which is suitably secured in 40 45 50 position upon the side piece A'. Within the space between the two pieces of wire-gauze a² and a³ in the inner and outer ends, respec-

tively, of the larger opening A⁰ is preferably placed a filling of sponge or other similar porous material, as shown at a⁴ in Figs. 1 and 2. 55

One end of the strainer rests upon the bottom of the well in practice, and the water or other liquid in order to enter the hollow space within the strainer must pass through the openings A⁰ and a⁰. The openings A⁰, leading to the outer sides of the strainer, being larger, present a larger filtering area for the water to pass through, and the inner openings a⁰, being smaller, present a contracted space for the escape of the water to the interior 60 65 of the strainer, thus insuring a perfect filtration.

When the filtering material and the wire-gauze become so clogged with sediment as to retard the operation of the strainer, the whole 70 strainer may be readily lifted bodily from the well and cleaned, or the old filtering material may be removed and new material put in its place, and the strainer may then be replaced in the well with ease and simplicity. 75

In Fig. 3, B represents a strainer of a quadrangular form—that is, made up of four side pieces B' of equal width, having their edges overlapping and secured together in any suitable manner, as at b'. The side pieces B' are 80 each provided with a plurality of larger outer openings B⁰ and smaller inner openings b⁰ and with pieces of wire-gauze b² and b³ over the inner and outer openings, respectively, and sponge or similar filtering material b⁴ between the said pieces of wire-gauze, all constructed and arranged in a precisely similar manner to the corresponding parts shown in Figs. 1 and 2 and above described. 85

In Figs. 4 and 5, C represents a strainer of a 90 cylindrical form and illustrates such a strainer as made of molded cement or a section of terra-cotta pipe. In this form of strainer the required number of openings C⁰ and c⁰ are arranged at proper intervals upon the shell of 95 the strainer, and the pieces of wire-gauze c² and c³ are preferably molded into the shell of the strainer.

The filtering material c⁴ shown may or may not be used, as desired, as also, however, 100 would be the case with the forms hereinbefore described.

The forms of strainers shown in Figs. 1, 2, and 3 may be made of pieces of heavy lum-

ber, as shown, or the same forms may be constructed of cement in suitable molds.

I do not wish to limit myself to any one or more of the forms shown and described herein, as it will be obvious to any one that the general form may be changed at will to suit conditions without departing from the spirit of my invention. Not only may the general shape of the strainer be varied, but the size ⁵ as well.

Having thus described my invention, what I claim, and desire to secure by Letters Patent of the United States, is—

1. In a well-strainer, the combination of a hollow shell or casing made up of a plurality of sections fitted together, and provided externally with a plurality of larger openings leading partially therethrough, and internally with a corresponding number of smaller openings leading to said larger external openings; a strainer covering the passage between each larger and corresponding smaller opening; and a strainer covering each larger opening, substantially as described. ¹⁵

2. In a well-strainer, the combination with a hollow shell or casing made of cement molded into the desired shape and provided externally with a plurality of larger openings leading partially therethrough, and internally ²⁰

with a corresponding number of smaller openings leading to said larger external openings; sheets of wire-gauze covering the inner ends of said smaller openings, and other sheets of wire-gauze covering the outer ends of said larger openings, said sheets of gauze being ³⁰ embedded at their edges in said cement, substantially as described. ³⁵

3. In a well-strainer, the combination with a hollow shell or casing made of cement, molded into the desired shape and provided externally with a plurality of openings leading partially therethrough, and internally with smaller openings leading to said external openings, sheets of wire-gauze covering the outer ends of said smaller openings, and other sheets of ⁴⁰ wire-gauze covering the outer ends of said larger openings, said sheets of gauze being embedded at their edges in said cement casing, and a porous filtering material filling the space between the parallel layers of wire- ⁴⁵ gauze, substantially as described. ⁵⁰

In testimony whereof I affix my signature in presence of two witnesses.

JOHN BOOTH.
